BOEHM SYSTEM CLARINET

Oscar E. Christensen, Salt Lake City, Utah

Application February 9, 1939, Serial No. 255,510

4 Claims. (Cl. 84—382)

This invention relates to improvements in clarinets and pertains particularly to the Boehm system clarinet.

In the present conventional Boehm system model clarinet, the tones Eb (first line of the staff) and Bb (second space above the staff) when played or produced by the finger position using only the first finger of each hand covering its respective tone hole (the thumb hole being covered for both tones and for the Bb, the twelfth or register key being opened) show a decidedly unbalanced quality of intonation.

If the tone Bb (played with the above described fingering) is properly tuned, the tone Eb is extremely sharp or high and if the tone Eb is properly tuned, then the tone Bb is extremely flat or low. The same situation exists between the tones E and B, to a slightly lesser extent, and the tones F and C are also slightly involved.

The present invention has for its primary object or purpose to provide a novel mechanism whereby there may be obtained a balance of the intonation of the tones Eb—E and F and Bb—B and C on a clarinet of the Boehm type.

Another object of the invention is to provide a mechanism whereby the above described object may be attained, which is of extremely simple design and which is made use of or operated without requiring any alteration in the regular or established fingering of the instrument.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Fig. 1 represents the upper main section of a clarinet showing the key mechanism embodying the present invention together with certain adjacent keys in spread out relation whereby the relative positions of the parts is more readily seen.

Fig. 2 is a sectional view on the line 2—2 of Fig. 1.

Fig. 3 is a sectional view on the line 3—3 of Fig. 1.

Fig. 4 is a sectional view on the line 4—4 of Fig. 1.

Referring now more particularly to the draw-

ing, the numeral 1 generally designates the upper main section of a clarinet of the Boehm type, the wall structure of which has been illustrated as laid out or flattened for the purpose of more readily illustrating the relative positions of the keys and tone holes.

The numeral 2 designates the standard register key pad which is actuated by the key 3 pivoted upon the shaft 4. Adjacent the key 3 is the usual thumb hole 5 by which the tones F 10 and C are played.

The numerals 6, 7 and 8 designate respectively the open tone holes of the conventional instrument by which are played respectively the tones E—B, D—A and C—G. The tone holes 6 and 7 15 normally have associated therewith the rings 9 and 10, respectively, and the ring 9 is supported for oscillation upon the shaft 11 and in the conventional Boehm system instrument, the ring 10 is also supported upon the shaft 11 to be 20 oscillated therewith, but in the present improved key arrangement, this ring 10 has a separate support which will be hereinafter described. Adjacent the tone hole 7, a covered tone hole is located over which lies the pad 12 which is also 25 carried upon the shaft 11 and which is closed simultaneously with the closing of the tone hole 7 by the second finger of the left hand.

Paralleling the shaft 11 is a shaft 13 upon which are oscillatably mounted the sleeves 14, 30 15 and 16. The sleeve 14 carries a pad 17 which overlies the Eb—Bb tone hole. Connected with the sleeve 16 is a pad 18 which covers a tone hole which is particularly described and claimed in my copending application, Ser. No. 223,545, filed 35 August 6, 1938, by which the F#—C# tones may be played.

In carrying out the present invention, there is provided a shaft 19 which is suspended by and passes through the aligned posts 20 and parallels the register key 3, preferably being disposed in the position shown, that is, between the register key and the shaft 13. Upon the shaft 19 are mounted for independent or joint oscillation the sleeves 21 and 22. The sleeve 21 carries an 45 arm 23 which overlies the register key 3, as shown, so that when this key is depressed, the sleeve 21 will be rocked. The extent of rocking movement of this sleeve is controlled by the movement limiting foot 24 which merely serves 50 as a safety device which prevents the accidental turning or rocking of the sleeve to an extent which might damage the spring 25 which is secured to a post and is connected with the sleeve in the conventional manner to cause the arm 23 55

to constantly bear upon the register key in order to maintain the pad 2 in closed position.

The sleeve 22 carries an arm 26 which in turn carries a pad 27 which normally closes a tone hole 28. At the opposite end of the sleeve 22, a finger 29 is supported by the sleeve which positions beneath a finger 30 upon the adjacent sleeve 21. Through the medium of these overlapping fingers 29 and 30, the spring 25 operates 5 to constantly maintain the pad 27 in closed position. There is, however, associated with the sleeve 22, a spring 31 which is of lighter tension than the spring 25 and which operates to insure the raising of the pad 27 when the register key 15 is depressed. When this key is released, the spring 25, naturally, because of its greater strength, overcomes the tension of spring 31 and forces both sleeves 21—22 to oscillate in the proper direction to close the pads 2 and 27.

20 As previously stated, the ring 10 is ordinarily supported for oscillation on and with the shaft 11 but in the present improved construction, this ring is carried on the shaft 13 by the sleeve 15 and is coupled with the normally raised pad 12, so that when the ring 10 is depressed, the pad 12 will also be depressed to close the underlying tone hole which is particularly illustrated in Fig. 2. The mechanism by which the ring 10 and pad 12 are joined together for the simultaneous closing of the pad with the depression of the ring or the closing of the tone hole 7 is particularly illustrated in Fig. 2, wherein the pad 12 has shown attached thereto the laterally extending bracket 32 which extends under the edge of the 35 adjacent ring and this ring is provided with a set screw 33 by which the proper adjustment may be made in the connection between the ring and pad so that they will operate smoothly and without noise.

40 Integral with the sleeve 15 with which the ring 10 is connected, is an arm 34 which extends laterally to a position beneath and is normally spaced from the arm 35 which is carried by the sleeve 22. The arm 34 operates to prevent the sleeve 32 oscillating and to prevent the pad 27 being raised when the tone hole 7 is closed and the register key is opened. As previously stated, when the register key is opened without the tone hole 7 being closed, or in other words, without the 45 ring 10 being depressed, then the pad 27 will be raised.

In the use of the instrument with the present improved mechanism, when the first or index finger of each hand is depressed or covering its tone hole for the playing B_b (second space above the staff) the register key 3 is depressed with the result that the additional tone hole 28 which is covered by the pad 27 will be opened or, in other words, the pad 27 will be raised. This will permit the passage of an additional amount of air through the tone hole to bring the B_b tone up to the proper pitch. This explanation is given or made with the understanding that the lower notes are first to be properly pitched or have been properly pitched in the instrument, in which case, without the addition of the tone hole 28, the playing of the B_b tone would be too low. By providing the additional tone hole 28, this is overcome and the B_b tone is brought up to the proper 70 pitch.

In playing the keys E and B, the key of E would be played by closing the tone hole with the index finger of the left hand, while the register key is in closed position. By opening the register key, 75 the tone B will be obtained and in the ordinary

instrument with the E properly tune, the B tone would be off or would be low. With the present improved device, when the register key is opened, the tone hole 28 is opened and the tone B will be brought up to proper pitch because of the additional air outlet provided by opening the hole 28.

In instruments where the F tone is properly tuned, the provision of the added tone hole 28 facilitates the playing of C at the proper pitch because of the fact that when the register key is opened for playing the tone C, the added tone opening 28 will be uncovered and this will bring the tone C up to the proper pitch which would be ordinarily tuned slightly low if the F is tuned correctly.

From the foregoing, it will be readily apparent that with the mechanism herein described, the proper pitches may be obtained for those tones which are ordinarily slightly off pitch in a conventional instrument and also that this mechanism has the added advantage of enabling the musician to obtain these tones at the correct pitch without making any changes in the conventional fingering of the instrument.

What is claimed is:

1. In a Boehm system clarinet, means for bringing the tones B_b, B and C (above the staff) to true pitch when the instrument is properly tuned to E_b, E and F (first line and first space of staff), which comprises the addition of a normally closed tone hole to the instrument, and means for opening said tone hole simultaneously with the opening of the register key only when the fingering is employed for producing the said tones B_b, 30 B and C, the said means being used for the tones E_b—B_b when using only the E_b—B_b fingering in which the first finger of each hand covers its respective tone hole.

2. In a Boehm system clarinet, means for bringing the tones B_b, B and C (above the staff) to true pitch when the instrument is properly tuned to E_b, E and F (first line and first space of staff), which comprises the addition of a normally closed tone hole to the instrument, means for opening said tone hole simultaneously with the opening of the register key only when the fingering is employed for producing the said tones B_b, B and C, the said means being used for the tones E_b—B_b when using only the E_b—B_b fingering in which the first finger of each hand covers its respective tone hole, and means for preventing the opening of the said added tone hole when the register key is open for producing all tones other than those first mentioned.

3. In a Boehm system clarinet, the mechanism for producing at true pitch the tones B_b, B and C (above the staff) when the instrument is properly tuned to produce the tones E_b, E and F, which comprises a two-part shaft in which each 60 part is mounted upon the instrument for independent oscillation, the instrument having a tone hole added thereto adjacent one of said shaft parts, a pad for said added hole carried by the said one of the shaft parts, an operative coupling between the other shaft part and the register key, means whereby the two shaft parts will be oscillated together to lift said pad and open the added tone hole, when the register key is opened for producing any one of the first mentioned 65 tones, and said means being designed to facilitate opening the register key while holding said pad against movement for the production of certain other tones.

4. In a Boehm system clarinet, the mechanism 75

- for producing at true pitch the tones B $\flat$, B and C when the instrument is properly tuned to produce the tones E $\flat$, E and F, which comprises a two-part shaft mounted adjacent the instrument
- 5 5
- 5 to register key, coupling means between said register key and one of the shaft parts by which opening of the register key will effect oscillation of the said shaft part, resilient means normally urging oscillation of the said one shaft part in a manner
- 10 10
- 10 to close the register key, the instrument having an added tone hole adjacent the other shaft part, a pad carried by said other part and normally closing said hole, resilient means normally urging oscillation of the said other part in a direction to remove the pad from the added tone
- 15 15
- 15 hole, connecting means between the shaft parts

which is so constructed and arranged that oscillation of the first-mentioned part upon opening of the register key will permit the second-mentioned resilient means to remove the pad from said tone hole, the first resilient means being of greater strength than the second and acting through said connecting means between the shaft parts to hold the pad seated over the tone hole when the register key is closed, and means for retaining the said pad in closed position on the added tone hole while fingering the instrument in the conventional manner when the register key is open for producing all tones other than those first mentioned.
